DESIGN.

E. W. BORGGRAFE,
CASING FOR RADIOPROJECTORS,
APPLICATION FILED JAN. 12, 1917.

51,250.

Patented Sept. 11, 1917.

Inventor

Edward W. Borggrafe

By Attorney

UNITED STATES PATENT OFFICE.

EDWARD W. BORGGRAFE, OF STAMFORD, CONNECTICUT, ASSIGNOR TO ELECTRIC SPECIALTY CO., OF STAMFORD, CONNECTICUT, A CORPORATION OF CONNECTICUT.

DESIGN FOR A CASING FOR RADIODESIGNATORS.

51,250.

Specification for Design.

Patented Sept. 11, 1917.

Application filed January 12, 1917. Serial No. 142,109. Term of patent 14 years.

To all whom it may concern:

Be it known that I, EDWARD W. BORGGRAFE, a subject of the Emperor of Germany, residing at Stamford, county of Fairfield, and State of Connecticut, have invented a new, original, and ornamental Design for a Casing for Radiogenerators, of which the following is a specification, reference being had to the accompanying drawing, forming part thereof, in which—

Figure 1 is a perspective view of a casing

for radio-generators illustrating my new design.

Fig. 2 an end view thereof.

I claim:

The ornamental design for a casing for a radio-generator, as shown.

EDWARD W. BORGGRAFE.

Witnesses:

T. W. SMITH, Jr.,

M. T. LONGDEN.
